UNITED STATES PATENT OFFICE

GORDON BROWN SCHEIBELL, OF DENVILLE, NEW JERSEY, ASSIGNOR TO WIRED RADIO INC., OF NEW YORK, N. Y., A CORPORATION OF DELAWARE

DESIGN FOR A CABINET FOR A COMBINED CLOCK AND RADIO

Application filed September 21, 1931. Serial No. 41,160. Term of patent 14 years.

To all whom it may concern:

Be it known that I, GORDON BROWN SCHEIBELL, a citizen of the United States, residing at Denville, in the county of Morris and State of New Jersey, have invented a new, original, and ornamental Design for Cabinet for Combined Clock and Radio, of which the following is a specification, reference being had to the accompanying drawings, forming part thereof.

In the drawings, Fig. 1 is a top plan view and Fig. 2 is a front elevation of a cabinet for combined clock and radio, showing my new design.

I claim:

The ornamental design for a cabinet for a combined clock and radio, as shown.

GORDON BROWN SCHEIBELL.
